(57) **CLAIM**

The ornamental design for a display screen or portion thereof with animated card communication interface, as shown and described.

DESCRIPTION

FIG. 1 is a first image in a sequence for a display screen or portion thereof with animated card communication interface showing the new design;

FIG. 2 is a second image thereof; and,

FIG. 3 is a third image thereof.

The appearance of the animated images sequentially transitions between the images shown in FIGS. 1 through 3.

The process or period in which one image transitions to another forms no part of the claimed design.

The long-dashed lines forming a portion of a rectangular shape in FIGS. 1 through 3 are included in the claimed design.

The short-dashed broken line showing of a display screen or portion thereof with animated card communication interface is included for the purpose of illustrating portions of the article; the short-dashed showing a device is included for the purpose of illustrating environmental structure and forms no part of the claimed design.

The short-dashed broken line showing of a display screen or portion thereof with animated card communication interface is included for the purpose of illustrating portions of the article; the short-dashed showing a device is included for the purpose of illustrating environmental structure and forms no part of the claimed design.
